SHOULDER PAD

William R. Gershen, Larchmont, N. Y.

Application July 8, 1944, Serial No. 543,975

4 Claims. (Cl. 2—268)

1

This invention relates to a shoulder pad and its general object is to provide pads that conform to the natural curvatures of the human figure, to give the shoulders of a garment the fanciful raised design, while, at the same time preventing bulges and bunches at sides of the garment, averting thereby also the wrinkling of the garment at the sides thereof.

An object of my invention is to confine the raised effect to that portion of the shoulders where such raised effect will enhance the natural appearance of the human figure.

Another object is to provide a concave base for the pad which will retain the shoulders shape of the garment in an even manner regardless of the posture of the wearer.

Another object is to form graduating curvatures on the pad to provide as a means to enable the garment to conform to the natural shape of the wearer.

Another object is to prevent the shifting and displacement of the raised portion of the shoulder thereby causing the garment to assume a proper fitting position, in all postures of the wearer.

Another object of my invention is to provide means of control for the accurate positioning of the pad arrangement on the garment.

Another object is to avoid intricate alterations to the garment, particularly the armhole and sleeve portions thereof, thereby avoiding the disturbing of the lining materials and the position of the sleeve members of the garment.

Another object is to provide a smooth side and underarm fit of the garment to which my invention is attached.

Another object of my invention is to construct a pad which will confine its extension to the convex upper portion only, and the concave base of which will not extend beyond the natural lines of the figure, providing thereby free arm movement.

A further object of my invention is to provide a simple and effective manner of construction at a minimum cost.

This invention also consists in certain other features of construction and in the combination and arrangement to be hereinafter fully described, illustrating these and other objects attained by the means and methods herein described and illustrated in the accompanying drawings, in which:

Fig. 1 is a plan view of the canvas piece forming the inner foundation member of the pad.

Fig. 2 is a plan view of the pocket forming

2

canvas piece of the inner foundation member of the pad.

Fig. 3 is a plan view of the inner foundation member canvas piece, having a layer of a fluff or wadding spread along the surface thereof.

Fig. 4 is the canvas inner foundation member of the pad with the canvas pocket forming portion stitched thereto.

Fig. 5 is the canvas inner foundation member of the pad with the pocket filled with a blank of plies of fluffy material.

Fig. 6 is a perspective elevational view of said blank cut into pyramid-like shape and consisting of plies of fluffy material.

Fig. 6a is a plan view of the blank consisting of plies of fluffy material.

Fig. 7 is a perspective elevational view of the blank consisting of plies of fluffy material, said plies having been tilted sidewise and repositioned thereby into a bias relation to the inner canvas member before insertion of said tilted plies into the canvas pocket of said inner member of the pad.

Fig. 8 is a plan view of the top portion of the fabric outer casing of the pad.

Fig. 9 is a plan view of the bottom portion of the fabric outer casing of the pad.

Fig. 10 is a plan view of the side portion of the fabric outer casing of the pad.

Fig. 11 is a perspective view of the three member portions of the outer casing of the pad, partially sewed together, and

Fig. 12 is a perspective view of the shoulder pad.

Shoulder pads have been suggested heretofore, but such pads served only as decorative means for extending shoulder forms which did not provide for the perfecting of fit, especially in the extending of its utility to the sides of the garment so that they would not bulge, wrinkle or gap, no matter what posture the wearer assumes.

Referring in detail to the drawings:

Canvas or other non-stretchable, stiff materials are employed to form a non-stretchable foundation for the inner structure of the pad.

Fig. 1 illustrates the canvas piece A which forms an inner foundation for the pad; upon said canvas foundation and along its entire surface a layer of wadding or other fluffy material is placed (see C, Fig. 3). Said layer C is distributed evenly along said surface A. Next, the canvas piece is taken as shown in Fig. 2 and is stitched to the padded canvas B. It will be noted that the upper portion of the canvas piece A is much larger than the bottom piece B. Preferably, the radius of the upper

piece B should be $\frac{2}{3}$ of the length of the radius A. Having secured the top piece A to the bottom piece B, the thus formed canvas pocket H (Fig. 5) is filled with the blank consisting of plies of fluff illustrated in Fig. 6. While the perspective view of the fluff G, Fig. 6, illustrates a pyramidal shaped cut of fluff, the use of blanks consisting of layers of fluff in other shapes is equally permissible though not preferable. Before inserting the blank of plies of fluff G illustrated in Fig. 6, said blank consisting of plies of fluff G is tilted sidewise (Fig. 7) thereby re-positioning the plies before inserting it within the canvas formed pocket H.

Fig. 7 illustrates the aforementioned re-positioned plies of fluff G tilted to a bias arrangement.

It will now be seen that a canvas walled pocket has been formed superimposing a canvas extension padded on one side to form the foundation for a pad. The canvas foundation with the fluff filled pocket thus formed, is now ready for encasement.

The outer casing can be of any textile fabric and is formed by three pieces, two pieces like Fig. 8 of the same dimensions as the canvas base Fig. 1, and one piece like U (Fig. 10) being semi-circular in shape.

The bottom fabric portion of the outer casing is darted invertedly on the line M—N, thereby being shortened in edge length on lines P—T and T—Q of Fig. 9, and also thereby forming a concave line at edge P—T—Q.

In the third fabric piece illustrated in Fig. 10, the diameter Z—X is slightly shorter than the widest portion of the dart M—N.

The semi-circular piece designated as Fig. 10 is joined along lines Z—U—X to the straight end of upper edge of the wall of the outer case of the pad designated as Fig. 8. Thereupon, the semi-circular piece designated as Fig. 10 is joined along lines Z—X to the bottom edge of the wall member designated as Fig. 9 of the outer case along lines P—T—Q. Thereupon, within the thus partially joined outer case member of the pad Fig. 11, the canvas inner foundation member 5 is inserted. I next close the sides K and L of the outer case along lines N'—P' and M'—P' and also lines Q'—N' and Q'—M'.

The darted bottom portion P—T—Q of the fabric outer casing having been shortened by the dart on line N—M will bend the stiff canvas inner foundation member A in arc-like manner.

The convex shaped bottom P—Q will at the same time pull on line 10 thereby forcing the stuffed pocket of the canvas inner foundation piece upwardly. This upwardly pressed stuffed pocket will be received in the additional rooming space (Fig. 11) N2 herein provided which additional room space is obtained by the addition of the extra piece Z—U—X illustrated in Fig. 10 added to the perimeter of the case.

While a darted bottom wall is illustrated for the outer casing as preferable, other means of shaping the bottom wall are also within the spirit of my invention.

I now have shown a springlike pad which exerts pressure in an outwardly upward direction, forming thereby a pad with a springlike extension at the upward portion of the pad, the sides of said pad being in arc like manner to hug the under-arm and to keep the sides thereof from wrinkling, the concave bottom of the pad sloping inward thus leaving the arm movements free, the concave bottom of the pad at the same time forming a firm resting means on the shoulder.

What I claim is:

1. A shoulder pad, including a stiff inner case member and a fabric outer case member, said stiff inner case member having a pliable foundation, said pliable foundation having a ply of fluffy material spread along its surface, and a stiff pocket portion stitched thereto, said pocket portion of the stiff inner case member being filled with a blank of plies of fluffy material, said blank being positioned in said pocket on a bias with respect to the normal position of the inner case member, said fabric outer casing consisting of top, bottom, and side wall members, said bottom wall member being distinguished in perimeter from said top wall member of said casing by an inverted dart, said dart being centrally placed in said bottom wall member, said side wall member having a rounded top edge and a straight bottom edge, the round upper edge of the said side wall member being adjacent to the top wall member of said outer casing, the straight edge of said side wall member being adjacent to the lower edge of said bottom wall member of said outer casing; all the edges of said wall members being stitched together, thereby forming an outer casing, said casing pliably bending the stiff inner foundation and forcing, thereby, said fluffy filled pocket of said stiff inner foundation upwardly towards the round edge of the front wall of said pad and drawing thereby to a convexed downward direction the front portion of the bottom side of the pad aforesaid.

2. A shoulder pad comprising an inner foundation of canvas or like stiffened material, and an outer casing of fabric, said inner foundation having a fluffy material spread thereon, a canvas pocket stitched to said inner foundation, a padding of fluffy material inserted in a bias relation to the inner foundation into said canvas pocket, said outer casing of fabric having top, bottom and side walls, said top, and bottom walls being of the same perimeter, and said side wall of said outer casing being round at one edge and straight at the outer edge thereof, the bottom wall of said outer casing being darted, the edge thereof being formed by said darting means into a downwardly convexed and narrowed width thereby bending the inner canvas foundation in arc formation and simultaneously forcing said fluff filled canvas pocket upwardly toward the rounded edge of the rounded wall member of the outer casing aforesaid.

3. A shoulder pad comprising a pliable stiff inner foundation and a fabric outer casing, said stiff pliable inner foundation having a fluff material evenly distributed along its surface, said stiff pliable inner foundation having a pocket of stiff material stitched thereto on the opposite side of said fluff material covering the surface of said pliable inner foundation, said pocket being filled with a blank consisting of plies of fluffy material, said blank being inserted in bias relation to the inner foundation, said outer fabric having top, bottom and side walls, a conforming top and bottom wall and a front wall, said bottom wall being darted at center thereof, thereby contracting in convexed form, the outer side of said bottom wall; the front wall of said outer casing having a rounded shape at top edge thereof and a straight bottom edge, said round edge of said front wall of said outer casing being adjacent to the front edge of said top wall of said outer casing, said straight edge of the front wall of said outer casing being adjacent to the front edge of said bottom wall of said outer casing, the inner

pliable stiff foundation being inserted within said outer casing with all members being stitched together thereby pliably bending the stiff inner foundation of said pad and bringing the sides of said pad together in arc-like shape, and also forcing said fluff filled pocket of said stiff inner foundation upwardly toward the round upper edge of the front wall of said outer casing of said pad, and drawing simultaneously the bottom portion of said pad in a convexed downward direction.

4. A shoulder pad, comprising a pliable stiff inner foundation and a fabric outer casing member, said stiff pliable inner foundation having a fluff material evenly distributed along the surface thereof, said stiff inner foundation having a pocket of stiff material stitched to the reverse side of said inner foundation, said pocket having a blank formed of plies of resilient material inserted therein, said blank being inserted into said pocket on a bias with respect to the normal

position of the inner foundation, said outer fabric casing having top, bottom, and front walls respectively, the bottom wall being shaped in conformity with said top wall and having the front edge thereof narrowed and convexed, said front wall of said outer casing being rounded at upper edge and straight at bottom edge thereof, said rounded edge being adjacent to the front top edge of said top wall and having the straight bottom edge of said front wall adjacent to the convexed edge of the bottom wall of said outer casing, the pliable inner foundation being inserted within said outer casing, and all the respective parts being stitched together at respective edges, thereby pliably bending the stiff inner foundation, forcing thereby the fluff filled pocket of said inner foundation upwardly toward the round edge of the front wall of said outer casing of said pad, and simultaneously pulling the bottom portions of said pad in a downward convexed direction.

WILLIAM R. GERSHEN.
